TREATING TOBACCO

Thomas E. Booth, Mountain View, N. J., assignor,
by mesne assignments, to The Guardite Corporation,
Chicago, Ill., a corporation of Illinois

Application January 25, 1939, Serial No. 252,817

2 Claims. (Cl. 131—140)

This invention relates to a method of treating tobacco.

In fumigating tobacco, it is customary to evacuate the container to a high vacuum followed by introduction of a fumigating gas. At times the tobacco is too dry for proper handling, and it is desirable to moisten it. I have found that by following substantially the fumigation cycle the tobacco may be readily moistened with steam and water.

The invention is illustrated in the drawing, in which Figure 1 represents a somewhat diagrammatic side elevation, in section, of the apparatus; and Figure 2 is a cross section along the line 2 in

Figure 1.

10 represents a steel container provided with a door 11 and an evacuating line 12 leading to a pump 13. Along each side of the container is a pipe 14, of about 1 inch internal diameter, and provided at intervals of about 15 inches with perforations 15 facing outwardly toward the wall of the vessel. These perforations are preferably about $\frac{1}{4}$ inch in diameter.

Leading to the pipe 14 is a steam line 16. Line 16 is connected to a boiler (not shown) which is adapted to supply wet steam thereto under pressures of say 45 pounds. Line 17 connecting line 16 to the boiler is provided with a valve 18. Another line 19 joins line 16 on a T, and is also provided with a valve 20. Both valves 18 and 20 are hand-controlled. Line 19 is connected to a hot water supply, which preferably delivers water at 130-140° F. under 65 pounds pressure.

In operation, the tank is evacuated to about 29 to 29 $\frac{1}{2}$ inches vacuum, after the tobacco has been placed inside it. Steam and water are then admitted respectively through the lines 17 and 19 and the perforations 15 in the manifold 14. The amount of water employed is very much in excess of that required to desuperheat the steam and, in fact, the steam employed is already somewhat super-saturated. The mixture of water and

steam passes into the manifold 14 and is sprayed from the holes 15 against the side wall of the container and then passes to the tobacco. Enough water is employed so that frequently 4 or 5 inches of it will be found upon the floor of the container 5 after the treatment is over.

The steaming operation is carried on until the pressure within the tank has risen to 10 to 20 inches absolute, after which both steam and water are shut off and the tank allowed to stand 10 for some time. The tank is uninsulated and acts as a condenser, so that the tobacco is gradually cooled off by evaporation of water therefrom. The pressure will sometimes drop as much as 2 inches in an hour, thereby materially cooling the 15 tobacco rather uniformly throughout.

I claim:

1. The method of moistening tobacco in a walled chamber which comprises subjecting the tobacco in the chamber to a high vacuum, admitting a stream of water to a stream of steam in a closed passageway, carrying the mixed stream for a distance through a confined passageway and then admitting the mixed stream of steam and water from such passageway to the 25 closed chamber directed toward and in close proximity to the walls of said chamber, and reflecting the mixed current of steam and water from said walls upon the tobacco.

2. The method of moistening an organic product in a walled chamber which comprises subjecting the product in the chamber to a high vacuum, admitting a stream of water to a stream of steam in a closed passageway, carrying the mixed stream for a distance through a confined 35 passageway and then admitting a mixed stream of steam and water from such passageway to the closed chamber directed toward and in close proximity to the walls of said chamber, and reflecting the mixed current of steam and water 40 from said walls upon the organic product.

THOMAS E. BOOTH.
